EGG CARTON

William J. De Reamer, Crown Point, Ind., assignor to Mapes Consolidated Manufacturing Company, Griffith, Ind., a corporation of Delaware

Application February 4, 1936, Serial No. 62,319

4 Claims. (Cl. 229—29)

This invention relates to moulded pulp cartons, it more particularly relating to a carton adapted to act as a carrier for eggs, although not necessarily limited to that purpose.

5 An object of the invention is to provide a carton which will be simple in construction, economical in manufacture and effective for the purpose for which it is designed.

A further object of the invention is to provide 10 a carton which will be sufficiently flexible to permit the cells thereof to yield sufficient to tightly hold the eggs or other articles contained therein, but at the same time stiff enough to give the necessary rigidity to prevent buckling.

15 A further object of the invention is to provide a carton formed of two complementary hinged halves, one of which is provided with flaps on the free edge thereof and the other so constructed as to receive those flaps.

20 Fig. 1 is a top plan view of the carton in the opened position.

Fig. 2 is a fragmentary top plan of the closed carton.

Fig. 3 is a fragmentary longitudinal section 25 taken on the line 3—3 of Fig. 1 in the lower half of the carton.

Fig. 4 is a fragmentary longitudinal section taken on the line 4—4 of Fig. 1.

Fig. 5 is a fragmentary transverse section on 30 the line 5—5 of Fig. 1.

Fig. 6 is a fragmentary transverse section on the line 6—6 of Fig. 1.

Fig. 7 is an end view of the opened carton.

Fig. 8 is an end view of a closed carton, the view being partly in elevation and partly in transverse section.

Referring to the drawing, in Fig. 1 the carton is shown in its opened position, and as can be seen, is composed of two halves, one of which, indicated at 1, is to be known as the upper half, while the half 2 is designated as the lower half. The two halves are connected to each other by the hinge portion 3. In Fig. 7 is shown an end view of the opened carton.

45 In order to provide a desirable stiffness for the carton when the carton is in an opened or closed position, each half is so formed as to have a series of longitudinal and transverse intersecting ribs, which in conjunction with the side and end walls of the halves, form egg-receiving depressions. Referring to the lower half 2, the longitudinal ribs are shown at 4 and 5. These ribs are hollow since this particular carton is preferably produced by a moulded pulp process, and in effect stand up from the flat sheet 6 of the half 1.

The longitudinal ribs 4 and 5 are crossed by the shorter intersecting transversely disposed ribs 7, 8, 9 and 10 also standing up from the flat sheet 6 and reaching the same height as the ribs 4 and 5.

The inwardly and downwardly sloping end and side walls of the half 2 are best seen in the sectional views, Figs. 3, 4, 5 and 6. The end wall for the left hand end is indicated at 11, Fig. 3, while the opposite end wall is shown at 12, Fig. 4. The outer and inner side walls of this half are seen at 13 and 14 respectively in Figs. 5 and 6. The end and side walls are formed to have the sloping effect for two reasons, one being that the carton is readily moulded, the other being that in conjunction with the previously mentioned longitudinal and transverse ribs, egg-receiving pockets are formed in which in reference to the carton half in question, the lower portions of eggs are received.

None of the ribs extends completely to either end or side walls of the half. As can be seen in Fig. 1, the left end of the longitudinal rib 4 stops short of the end wall 11, the sloping end 15 of the rib 4 meeting the sloping end wall 11 at the latter's connection with the flat sheet 6. By stopping the rib short of the end wall as described, the effect is that a V-shaped depression 16 is formed across the end of the lower half as viewed from above, as in Fig. 1. However, since the moulding process produces comparatively uniform wall thicknesses throughout the carton, the effect is further that a hollow rib 17 is formed across the end of the half which greatly strengthens the lower half at this point, this rib being inverted with respect to the ribs 4, 5, 7, 8, 9 and 10. The same feature is true in reference to the opposite end of the half, since the longitudinal rib 5, in being stopped short of the end wall 12, forms at this end the inverted rib 18.

40 Inverted ribs of the same nature are formed at the center of the lower half 2 for the same purpose, since the adjacent ends of each of the longitudinal ribs 4 and 5 are stopped short of a central rib 19, the inverted ribs here being indicated at 20 and 21 on either side of the central rib 19 (Figs. 3 and 4).

45 The transversely extending ribs 6, 7, 8 and 9 also are not extended to the side wall of the lower half for a similar purpose, i. e., of providing the inverted longitudinal strengthening ribs seen at 22 and 23, Figs. 5 and 6. The inverted rib 22 has another function, that is, since it is a hollow rib as are all the other ribs, a series of V-shaped lon-

itudinally extending depressions 24, as viewed from above as in Fig. 1. The purpose of this formation is to aid in keeping the closed carton in a condition whereby accidental opening is minimized, which is explained as follows:

The upper half is formed so much like the lower half that the description thereof will be limited to its variation from the lower half, it being first mentioned that in order to provide an upper half 10 which will fold over and close down on the lower half, the construction of the upper half is complementary to the lower half. The difference between the halves is that for the upper half, along the edge opposite the hinge portion 3, there is 15 provided a flap portion 25 which, for the present purpose, is hingedly connected integrally with the upper half, and is thereby capable of being bent along the broken line 26 (Fig. 1). When eggs are placed in the pockets and the upper half closed 20 over, as shown in Fig. 8, the flap 25 is bent downwardly and forced inwardly into the depressions 24 alongside the side wall 13. In this view, the eggs are shown by broken lines E, and it can be seen that the lower edge of the flap 25 is forced 25 between the eggs in the outer row and the side wall 13, whereby the friction of the flap so held is sufficient to prevent accidental opening of the carton.

To provide further against accidental breakage 30 of the enclosed eggs, the pockets are made sufficiently small so that in pressing an egg into a pocket, the hollow ribs yield to the pressure, this feature also being true as regards the corresponding ribs of the upper half when the same is closed 35 down over the lower half. As a further precaution, there is provided in each pocket, at the bottom, when reference is made to the lower half and at the top when referring to the upper half, a small hollow boss such as is indicated at 27 in 40 the views. These hollow bosses are comparatively resilient and yield somewhat to the egg pressure, and prevent the eggs from receiving damage when the carton is laid upon a hard surface.

Having thus described my invention, I claim:

1. In a moulded pulp carton, two halves hinged together, each of said halves having centrally arranged longitudinal ribs and transverse ribs intersecting said longitudinal ribs, said ribs coacting to form egg cells, the ribs of each half terminating short of the walls thereof, one of said halves being provided on its free side edge with at least one flap adapted to be tucked into the other complementary half between the transverse ribs and 10 the side wall thereof.

2. In a moulded pulp egg receptacle, a carton member having end and side walls, a pair of centrally arranged aligned longitudinal ribs each of equal height throughout and with each other, 15 transverse ribs, one of said transverse ribs being centrally arranged with respect to the length of the carton member and lying between said longitudinal ribs, the other transverse ribs being integrally formed with said longitudinal ribs. 20

3. In a moulded pulp egg receptacle, a carton member having end and side walls, a pair of centrally arranged aligned longitudinal ribs each of equal height throughout and with each other, 25 transverse ribs, said ribs coacting to form egg cells, one of said transverse ribs being centrally arranged with respect to the length of the carton member and lying between said longitudinal ribs, all of said transverse ribs save the centrally arranged rib being each integrally attached from 30 bottom to top to its companion longitudinal rib.

4. In a moulded pulp egg receptacle, a carton member having end and side walls, a pair of centrally arranged aligned longitudinal ribs each of equal height throughout and with each other, 35 transverse ribs, one of said transverse ribs being centrally arranged with respect to the length of the carton member and lying between said longitudinal ribs, the other transverse ribs being integrally formed with said longitudinal ribs, the 40 upper portions of said transverse ribs all terminating short of the sides of said carton member.

WILLIAM J. DE REAMER.
